MAGNETRON CIRCUIT CONTROLLING APPARATUS

Application filed August 13, 1924. Serial No. 731,694.

This invention relates to an electron discharge circuit controlling apparatus, and more particularly to a magnetron controlled circuit controlling apparatus designed for producing persisting circuit changes in response to momentary electrical influences; and has special reference to the provision of improvements in the magnetron circuit controlling apparatus described and claimed in my copending application Serial No. 650,803, filed July 11, 1924.

As disclosed in my said copending application, the magnetron circuit controlling apparatus of my invention consists in a magnetically controlled electron discharge device for controlling and producing persisting changes in circuits in response to magnetic influences of short duration, the same being serviceable, for example, in train control systems of the non-contact type as disclosed in my copending application Serial No. 566,565, for train control systems, filed June 7, 1922. In train control systems of this type, vehicle carried apparatus cooperates magnetically with roadside apparatus for producing train control indications in response to and in accordance with roadside or track conditions; and a desideratum in the operation of a system of this type centers about the production of vehicle carried apparatus which is instantaneous in its operation and which may be made immediately responsive to the roadside apparatus, especially when the vehicle carried apparatus passes or moves over the roadside apparatus at very high speeds. The present invention is especially adapted for service in such train control systems, the desired sensitiveness and rapidity of operation being attained by the substantially inertialess characteristics both mechanically and electrically of the magnetron apparatus.

In providing a substantially inertialess train control system effective so that an indication may be "picked up" and retained by a fast moving train passing a control point or station, essential desiderata are that (a) the instrument which receives the impulse from the roadside be substantially inertialess, so that at the very high speeds it will

respond to a governing impulse from the roadside no matter how short the impulse or how great the speed of the train, and that (b) a translating means or relay which is connected to the receiving instrument should be so associated with the receiving instrument as to have little or no retarding or reactive effects thereon, to the end that the characteristics of the receiving instrument alone be dominant in determining the rapidity of response of operation of the system as a whole. The provision of an improved receiving instrument and an improved organization of such receiving instrument with the translating means to produce the desired results is a prime object of my present invention.

More specific objects of my present invention include the provision of a magnetron circuit controlling apparatus which operates in response to magnetic impulses of short duration to produce persisting circuit changes and in which means are provided for supplementing the action of the magnetron when a circuit changing governing impulse is received to assist in making the circuit change effectual, and to prevent a lapsing or return of the magnetron to its former or unchanged state due to inertia of circuits controlled by and reacting upon the magnetron; the further provision of a combined magnetron and relay or translating means designed so that the inductance of the magnetron controlled circuit is reduced to a minimum, this to reduce the reacting inertia effective on the magnetron; the still further provision of circuit controlling apparatus in which a magnetron and a relay are combined so that all of the circuits connecting the magnetron and the relay are normally "safe," a breaking of any of the circuits producing a tell-tale operation of the relay.

To the accomplishment of the foregoing and such other objects as may hereinafter appear, my invention consists in the elements and their relation one to the other, as hereinafter particularly described and sought to be defined in the accompanying claims; reference being had to the accompanying drawings, which show the preferred

embodiments of my invention, and in which:—

Fig. 1 is a diagrammatic view of the combined magnetron and relay system of my invention,

Fig. 2 is a view of a modification thereof,

Fig. 3 is a graphical representation depicting characteristics of the apparatus and of the underlying principles of the invention, 10 and

Fig. 4 is a view of the electron discharge device or magnetron showing the structural arrangement of the parts.

Referring now more in detail to the drawings, and having particular reference to Fig. 1, the circuit controlling apparatus of my invention comprises the improved electron discharge device or magnetron M which is constructed so as to respond to momentary 15 magnetic influences produced for example by the movement of the magnetron M in the direction indicated by the arrow in Fig. 1 over relatively stationary magnetic means m, which latter in train control systems is located and arranged at fixed controlling points or stations along the roadbed, the magnetron M being carried by a moving vehicle, the said magnetron being connected for controlling the operation of a translating means or relay R which in turn controls the operation of train control circuits.

The electron discharge device or magnetron M comprises a vacuous vessel or envelope 10 provided with a linear filament or cathode 11 and with a cylindrical anode 12 encircling the cathode and arranged in circular symmetry therewith; and in the form of the invention illustrated in Fig. 1, the device is provided with means for creating controlling 20 magnetic fields, the said means comprising the solenoids 13 and 14 arranged as will be detailed hereinafter in independent circuits, the said solenoids being provided for selectively controlling the activity of the electron discharge device. In the diagrammatic illustration of Fig. 1, these solenoids for purposes of clarity have been shown arranged at the sides of the vessel 10, but it will be understood that the actual construction comprises a symmetrical arrangement of these solenoids encircling and surrounding the tube as shown in Fig. 4, the solenoids being coaxial and arranged in circular symmetry with the anode 25 and cathode of the device.

For heating the filament or cathode 11 to obtain the desired emission of electrons, the terminals of the same are connected together to a glow circuit b including the battery or other source of energy 15, the opposite poles of which are connected to the terminals of the filament by means of the conductors 16 and 17. As is well known, upon heating the filament 11 to incandescence by means of this 30 glow circuit, there takes place an emission of

electrons from the filament 11, which electrons will impinge upon the anode 12.

The electron flow between the anode and cathode controls a circuit generally designated as c, the said circuit including the positive terminal 18 of a source of energy, an operated element such as the coil 19 of the relay R, the conductor 20, the controlling solenoid 14, a conductor 21 connected to the anode, the cathode 11, and conductor 16 connected to the negative terminal 22 of the said source of energy.

The relay R in the present form of my invention is especially designed to cooperate with the governing circuits of the magnetron M so as to minimize inductive reactive effects of the former on the latter and so as to permit the obtaining of connecting circuits which are normally "safe", this relay comprising a plurality of coils 19 and 23, the former consisting of an armature coil mounted on the armature 24 pivoted as at 25, the said armature being weighted as at 26 and provided with the contact 27, the said armature being over-balanced on the side of the contact, so that upon failure of current in the armature coil 19 or any part of the circuit c, the armature will drop to open the contact 27. Both the armature and field coils 19 and 23 are circular, the latter being mounted on a core member having a central core 28 and a circular core 29 defining an annular air space in which the armature coil 19 is movable, the cooperation between the cores being such that the armature is repelled and the contact 27 thereof closed only when current is supplied to both the field and armature coils, this contact being opened upon failure of current in either of the relay coils.

The field coil 23 is connected in circuit with the controlling solenoid 13 of the magnetron in a circuit d, both being energized from the source of energy having the terminals 18 and 22, the circuit consisting of the terminal 18, the conductor 30, the coil 23, a resistance 31, a conductor 32, solenoid 13, and conductor 16 back to the negative terminal 22 of the source of energy. Normally all of the circuits b, c and d are closed, the magnetron M being energized with the electron emission from the cathode impinging upon the anode and the coils of the relay R energized to close the contact 27 thereof.

As is known, in the absence of any magnetic influence on the electron discharge device or magnetron M, the magnetron will be energized and a current will flow through the controlled circuit c. It is also known that when the magnetron is subjected to the influence of a magnetic field above a predetermined or critical magnitude, the electron flow between the cathode and anode will be interrupted for deenergizing the magnetron and deenergizing the controlled circuit c.

This phenomenon is graphically illustrated in Fig. 3 of the drawings, this figure representing the operating characteristics of the magnetron under the influence of a magnetic field, the strength of the magnetic field being represented by the abscissæ and the strength of the current in the output or controlled circuit *c* by the ordinates, the curve EDAB depicting the characteristics of the magnetron and controlled circuit. If the strength of the magnetic field influencing the magnetron is less than the abscissæ represented by CD, the electrons emitted from the cathode impinge uninterruptedly upon the anode, and the current in the controlled circuit *c* will be a maximum as represented by the ordinate XC. If, however, the strength of the magnetic field exceeds the critical point represented as D, the electrons will be diverted and prevented from reaching the anode 12 and the current in the output or controlled circuit *c* will suddenly fall to a value as represented by the part of the curve AB. From this it will be seen that the magnetron may be controlled by controlling in a predetermined manner the magnetic influence to which it is subjected.

For controlling the operation of the magnetron and the condition of the circuit *c* in accordance with my invention, I provide means as disclosed and claimed in my aforesaid copending application Ser. No. 650,803 and in Fig. 1 of the drawings herein for producing opposed magnetic fields influencing the magnetron, the said opposed magnetic fields having a given resultant magnitude, which magnitude is selectively changed and re-established to produce different conditions of operation. To this end the solenoids 13 and 14 heretofore referred to are so wound and arranged on the magnetron vessel 10 as to produce magnetic fields in opposition as depicted by the arrows in Fig. 1 associated with said solenoids, the strength of the opposing magnetic fields being so predetermined that the magnetic field produced by the solenoid 13 when acting alone is effective for establishing one condition of operation, and the strength of the resultant of both magnetic fields acting in opposition is effective for producing a different condition of operation. These predetermined magnitudes are graphically illustrated in Fig. 3 of the drawings, the strength of the magnetic field due to the solenoid 13 being indicated by the arrowed line M', the value of this field being greater than the critical value of the curve EDAB, this magnetic field being therefore sufficient when acting alone to close the magnetron and to deenergize the controlled circuit; and the strength of the opposing magnetic field produced by the solenoid 14 is indicated by the opposing arrowed line O, the inter-reaction of the fields M' and O being such as to produce a resultant field in-

dicated by the arrowed line R', this resultant being of a value less than the critical value of the curve and insufficient to disturb the energized magnetron and the energized circuit *c*, the value of the current in the circuit being then represented by the asterisk on the curve, Fig. 3.

As heretofore mentioned, for producing different operations of the magnetron and the controlled circuit, the resultant magnetic field is modified and re-established, the modification of the resultant field rendering the magnetron inactive, and the re-establishing of the field effecting the re-establishing of activity of the magnetron. These results may be accomplished in a number of ways, and in the construction exemplified in Fig. 1, I provide means for compensating or neutralizing the effect of the opposing magnetic field when the circuit *c* is to be deenergized and means for re-establishing this effect when re-energization of the circuit is desired, the said means comprising the spaced magnets *m* and *m'*, the magnetron being brought under the influence of the magnet *m* for deenergizing the circuit *c* and under the influence of the magnet *m'* for effecting the re-energization thereof. When the apparatus shown in Fig. 1 is designed as a train control system, the magnetron and its associated circuits are carried by a vehicle and the magnets *m* and *m'* are arranged in spaced relation along the roadside.

The magnet *m* has its poles arranged to oppose the opposing magnetic field of the solenoid 14 or to aid the main magnetic field of the solenoid 13, which latter may be combined with an assisting vehicle carried magnet 33 having the poles NS arranged to produce a magnetic flux assisting that obtained by the solenoid 13, the influence of the magnet *m* being such that the effect of the opposing magnetic field O is neutralized so that the main field M' alone is active for deenergizing the magnetron and deenergizing the circuit *c*. It will be noted that although the influence of the magnet *m* is but momentary in the passage of the magnetron thereover, the deenergization of the circuit *c* deenergizes the solenoid 14, and the opposing magnetic field O obtained by this solenoid is therefore removed so that a sustained deenergization of the circuit *c* is effected.

The magnet *m'* is arranged with its poles reversed relatively to those of the magnet *m* so that the said magnet *m'* is active to oppose the main magnetic field M' of the solenoid 13, and thus when the magnetron moves over the magnet *m'*, the momentary influence of the latter is sufficient to produce a resulting field less than the critical value of the magnetron, this influence producing an energizing of the magnetron and a re-energization of the circuit *c*. When the circuit *c* is re-energized, it will be seen that the solenoid

14 therein is also re-energized and thus the opposing magnetic field O of the solenoid 14 becomes effective to sustain the energization of the controlled circuit and to cause the same to persist after the magnetron passes beyond the magnet m'.⁵

From the foregoing, it will therefore be seen that under normal conditions the magnetron M is energized and the controlled circuit energized with the magnetic fields M' and O in opposition, the said circuit being maintained energized by the energization of the solenoid 14 therein, and that when the effect of the opposing magnetic field O is neutralized by a momentary magnetic impulse, the magnetron is deenergized and the circuit CD energized, and when the magnetron is influenced to produce an effect equivalent to the effect of the opposing magnetic field, the magnetron is reenergized and the controlled circuit c reenergized.²⁰

As heretofore mentioned, a principal object of my present invention centers about the provision of an improved magnetron designed so that the action of the same when a circuit changing governing impulse is received thereby is supplemented so as to assist in making the circuit change effectual and to prevent a lapsing or return of the magnetron to its former or unchanged state due to any inertia of the circuits controlled by and which may react upon the magnetron. I have discovered that when the controlled circuit c is shunted by a substantial inductance, the operation of the magnetron both for energizing and deenergizing the same is materially assisted when a momentary impulse is received. The action of the inductive shunt circuit may be explained as neutralizing or minimizing the effect of the inductance of the controlled circuit such as the inductance of the relay coil or the opposing solenoid therein. This inductance may be connected in shunt with the opposing solenoid 14, the latter being shown in Fig. 1 of the drawings, the inductance comprising preferably a closed core coil 34 connected in the shunt circuit s, the said circuit being provided with a series resistance 35 which is used to reduce the current consumption of the shunt path.⁴⁵

Without desiring to be limited to any theory of operation, the supplemental effect of the inductive shunt during the energizing or deenergizing of the magnetron may be explained as follows. When the magnetron receives a deenergizing impulse, due to the inductance of the relay coil in the controlled circuit and the inductance of the solenoid 14, the current in the circuit will fall only gradually, and it may occur that before the current has reached the desired low value for deenergizing the magnetron, the magnetron may have moved past the roadside controlling elements, and as a consequence the magnetron may lapse or return to its former state⁵⁵

or condition. The shunt inductive path, when the magnetron is energized, stores energy so that when such a deenergizing impulse is received, the shunt circuit will have a fly wheel or inertia effect, the current there-⁷⁰ in maintaining itself and flowing through the solenoid 14 in a direction opposite to the normal flow of current therein, with the result that the magnetization of the solenoid 14 is quickly brought to the low or zero value.⁷⁵ Conversely when the magnetron without the shunt inductive path receives an energizing impulse, the current in the controlled circuit builds up gradually due to the inductance of the parts therein, and the operation might prove to be such that before the current in the solenoid 14 reaches its desired value, the magnetron may pass beyond the track magnetic influence, which may result in a lapsing of the magnetron to its former or deenergized condition.⁸⁰ With the shunt inductive path when the magnetron receives an energizing impulse the shunt inductance offers a very high inductive and resistance path, and there is produced a current surge through the opening solenoid 14, which associated with the comparatively low inductance of the armature relay coil permits a quick and effective energizing of the relay.⁸⁵

Referring now to Fig. 2 of the drawings, I show a modification of the invention in which the inductance of a relay element is utilized for the shunt path. In this form of the invention the shunt path is the controlled circuit c', the said shunt path including the armature coil 19, the conductor 20, a supplementary inductance 36 if desired, the conductor 37 connected to the conductor 21 which in turn is connected to the anode 12. The solenoid 14 is in a second controlled circuit c² which includes the conductor 21 connected to the anode 12, solenoid 14, conductor 38, a resistance 39 connected to the positive terminal 18 of the source of energy, the negative terminal 22 of which is connected to the cathode 11 by means of the conductor 16. The other parts of the magnetron M and the relay R and the connecting circuits are similar to those heretofore described in connection with Fig. 1, and are denoted by similar reference characters.¹⁰⁵

As applied to the invention shown in Fig. 2, the shunt inductive path provides a fly wheel or inertia effect to produce a current in the coil 14 opposing the current therein¹²⁰ when a deenergizing magnetic impulse is received by the magnetron, thus quickly bringing the magnetization of the coil down to a low or zero value, and conversely upon receiving an energizing impulse, the very low inductance of the circuit of the coil 14 together with the supplemental action of the shunt circuit thereon will produce very rapid energizing of the magnetron.¹²⁵

The use and operation of my improved

magnetron circuit controlling apparatus will in the main be apparent from the above detailed description thereof. It will be further apparent that the supplemental or shunt 5 circuit renders the system independent of the particular characteristics of the relay or other controlled device connected to the magnetron, and is made dependent only upon the inertialess characteristics of the magnetron 10 device. It will be further seen that by the new organization between the relay and the magnetron of the present invention, the relay is also made to quickly respond to changes of indications, and the connections between 15 the magnetron and relay are such as to produce "safe" operating circuits to satisfy all the safety requirements in a train control system.

While I have shown and described my invention in the preferred forms, it will be obvious that many changes and modifications may be made in the structure disclosed without departing from the spirit of the invention, defined in the following claims.

25 I claim:

1. In combination, an electron discharge device having cathode and anode electrodes, a circuit connected to the electrodes and controlled by the electron flow therebetween, 30 mechanism for changing the condition of said device to modify the condition of the controlled circuit including a solenoid in said circuit for producing a magnetic field influencing the said device, and a relay having two coils one of which is arranged in 35 circuit with said electrodes.

2. In combination, an electron discharge device having cathode and anode electrodes, a circuit connected to the electrodes and controlled by the electron flow therebetween, 40 mechanism for changing the condition of said device to modify the condition of the controlled circuit including a solenoid in said circuit for producing a magnetic field influencing the said device, and a relay having a field coil and an armature coil, the 45 said armature coil being arranged in circuit with said electrodes.

3. In combination, an electron discharge 50 device having a cathode and an anode, a circuit connected to the cathode and anode and controlled by the electron flow therebetween, a solenoid producing a magnetic field active on said device, a second solenoid in said circuit for producing a magnetic field also influencing the said device, and a relay having 55 two coils, one of which is arranged in circuit with said first solenoid and the other of which is arranged in circuit with the second 60 solenoid.

4. In combination, an electron discharge 65 device having a cathode and an anode, a circuit controlled thereby, a solenoid producing a magnetic field active on said device and effective for establishing a given condition

therein and in said circuit, a second solenoid arranged in said circuit for producing a magnetic field acting in opposition to the first-mentioned magnetic field for establishing a different condition in said device and in said circuit, and a relay having two coils, 70 one arranged in circuit with said first solenoid and the other arranged in circuit with the anode and cathode of the device.

5. In combination, an electron discharge 75 device having a cathode and an anode, a circuit controlled thereby, a solenoid producing a magnetic field active on said device and effective for establishing a given condition therein and in said circuit, a second solenoid arranged in said circuit for producing a magnetic field acting in opposition to the first-mentioned magnetic field for establishing a different condition in said device and in said circuit, and a relay having a field coil 80 and an armature coil, the field coil being arranged in circuit with one of said solenoids and the armature coil being arranged in circuit with the anode and cathode of the device.

6. In combination, an electron discharge 85 device having a cathode and an anode, a circuit controlled thereby, a solenoid producing a magnetic field active on said device and effective for establishing a given condition 90 therein and in said circuit, a second solenoid arranged in said circuit for producing a magnetic field acting in opposition to the first-mentioned magnetic field for establishing a different condition in said device and in said circuit, and a relay having a field coil 95 and an armature coil cooperating for closing a contact relay only when current is supplied to both coils, the said field coil being connected in circuit with the first solenoid and the said armature coil being connected in circuit with the anode and cathode of the device.

Signed at Niagara Falls, in the county of Niagara and State of New York, this 1st day 110 of August, A. D. 1924.

THEODORE BODDE.
